UNITED STATES PATENT OFFICE.

JOSEPH T. ROFFY, OF BROOKLYN, NEW YORK, ASSIGNOR TO NATIONAL CARBON COMPANY, INC., OF NEW YORK, N. Y., A CORPORATION OF NEW YORK.

FLASH LIGHT.

Application filed January 2, 1920. Serial No. 348,925.

This invention relates to improvements in flashlights, and has for an object to provide means whereby the rays of light from the bulb can be focused without moving or adjusting the bulb in its socket. The manner of accomplishing this result will be set forth in the following specification, reference being had to the accompanying drawing wherein:—

10 Figure 1 is a sectional view broken away and partly in elevation of a flashlight embodying my improvement.

15 Figure 2 is a sectional view, partly in elevation, of a modified form of my invention, and

Figure 3 is a detail top plan view of the bulb-holder illustrated in Figure 2.

The form of flashlight herein selected to illustrate my improvement consists of a tubular casing 1 constructed to retain a battery 2 of the usual variety. Threaded upon one end of the casing is the rotatable head 3. At the other end of the casing 1 is the threaded cap 4 carrying the usual spring 5 for pressing the battery 2 into contact with the bulb. The incandescent lamp bulb 6 is carried by a support 7 and is threaded into the socket or bulb holder 8 thereon. The support 7 is insulated from the shell or casing 1 by the bushing 9 of insulating material and substantially closes one end of said casing. As will be evident, the head 3 is adapted to be rotated spirally for shifting it in the direction of the axis of the casing. The head 3 carries a glass 10 and a concave reflector 11, the head and reflector assembly being insulated by the bushing 9 from the support 7 and lamp holder 8. The reflector 11 is provided with a central opening 12 to permit of

40 the removal or application of the head independently of the bulb, the bulb being positioned centrally within the opening and out of contact with the reflector 11. As will be evident, when it is desired to focus the light emitted by the bulb, the reflector 11 need only be moved toward or away from the bulb in the direction of the axis of the shell by rotating the head 3. In order to maintain the head in any adjusted position, after the light has been properly focused, a set-screw 13 is provided. This set-screw is carried by the head 3 and passes through the

threaded boss 14 for engagement with the casing 1. In operation the focus of the light may be changed at will by loosening the set-screw 13 and adjusting the head in the manner described.

55 In the modified form of device illustrated in Figure 2, the support 15 is provided, having a yieldable resilient bottom 16, the resiliency being secured by the slots 17. In other respects the support 15 is similar to the support 7 illustrated in Figure 1, and the casing 1 similarly carries the reflector, lamp, lamp holder, and battery in axial alignment. To change the position of the bulb relatively to the reflector in the device shown in Figure 2 for focusing, the cap 4 threaded upon the lower end of the casing 1, will be rotated, thereby adjusting the tension of the 60 spring 5, and the pressure upon the battery 2 and the bulb 6. The battery and the bulb holder carrying the bulb are thus adjustable as a unit axially of the reflector and casing, and the center electrode of said battery is 65 maintained in electrical connection with the lamp during such focusing adjustments. It will be evident that the resiliency of the bottom 16 of the support 15 will permit considerable movement of the bulb-holder 8 and 70 the bulb relatively to the reflector and allow the light to be easily focused by merely rotatably and axially adjusting the cap 4. The upper limit of the movement of the bulb is indicated on the drawing by dotted lines. 75 When the bulb has been adjusted forwardly, the resilient bottom 16 between the reflector and the battery acts as a spring means to shift the bulb 6 in the reverse direction, i. e. rearwardly axially of the reflector, when the 80 cap 4 is unscrewed.

85 To close the electrical circuit in both forms of my improved flashlight, I employ a switch mechanism, consisting of a slideable circuit closer 18 operated in the usual manner by the button 19. The bottom face of each of the supports 7 and 15 has a disc of insulating material 9' secured thereto to serve as an abutment for the battery and insulate the latter from the lamp support when 90 the lamp is removed from its socket or broken, thus preventing short-circuiting of the battery.

95 It is to be understood that the invention

is not limited to the examples herein shown but may be practiced in various other ways.

Having described my invention, what I claim is:

5. 1. A focusing flashlight comprising the combination of an incandescent lamp; a battery for energizing said lamp; a reflector having an opening through which said lamp projects; a holder carrying said lamp; a casing carrying said reflector, holder, lamp, and battery in axial alinement; and means for adjusting said holder and said lamp axially relatively to said reflector and said casing, such adjusting means comprising 15 means rotatably and axially adjustable relatively to the axis of said casing, and said battery having a center electrode that is maintained in electrical connection with said lamp during the operation of such adjusting means.
2. In a flashlight, a casing, a yieldable bulb-holder at one end thereof consisting of a slotted plate, a bulb carried by the holder, and projecting therethrough, a battery in 25 the casing bearing against said bulb, and means to move the battery longitudinally of the casing to cause said holder to spring to change the focal position of the bulb.
3. In a flashlight, a casing, a yieldable bulb-holder at one end thereof consisting of a slotted plate, a bulb carried by the holder, and projecting therethrough, a battery in 35 the casing bearing against said bulb, and a rotatable cap at the opposite end of the casing to move the battery longitudinally of the casing to cause said bulb-holder to spring to change the focal position of the bulb.
4. In a portable electric light, a casing, a lamp, a focusing reflector therefor, means for energizing the lamp, means for moving the reflector, a yieldable holder for said lamp, and means for moving the lamp and holder in said casing to focus the light.
45. 5. In a battery hand lamp, the combination of a casing, a battery of dry cells therein, a lamp electrically connected with one terminal of said battery, a socket in which said lamp is threaded, a yielding support for said socket, a reflector insulated from said socket, and means for establishing electrical connection from the other terminal of said battery to said socket.
6. In a battery hand lamp, the combination of a battery, a lamp in operative relation thereto, a casing for said battery, a resilient disc closing the end of said casing and in which said lamp is mounted, and a reflector for said lamp removable therefrom without disturbing the operative relation of said lamp to said battery, substantially as described.
7. In a battery hand lamp, the combination of a battery, a casing therefor, a lamp, a

socket for said lamp, a yielding disc closing 65 the end of said casing and supporting said socket, a reflector insulated from said socket and having a central opening through which the lamp bulb will pass, and means for detachably supporting said reflector in operative relation to said lamp.

8. In a battery hand lamp, the combination of a battery, a lamp in operative relation thereto, a socket for said lamp, a yielding disc engaging and supporting said 75 socket to cushion any impact of the battery on said lamp, a reflector insulated from said socket, and means for moving said reflector with respect to said socket when the distribution of light from said lamp is to be 80 altered.

9. In a battery hand lamp, the combination of a casing, a battery therein, a lamp electrically connected with one terminal of 85 said battery, an adjustable socket for said lamp, a reflector insulated from said socket and adjustable axially of said casing and relatively to said lamp, means operable to adjust said socket and lamp relatively to said reflector, and means for establishing 90 electrical connection from the other terminal of said battery to said socket.

10. In a battery hand lamp, the combination of a battery, a casing therefor, a lamp connected with said battery, a reflector for 95 said lamp, a socket for said lamp, movable with respect to said reflector, a disk of insulating material secured to said socket and serving to insulate the same from the battery when the lamp is removed from the 100 socket, means for completing the battery circuit through said lamp, and means for moving said battery to focus said lamp in said reflector.

11. In a battery hand lamp, a casing, a 105 yieldably mounted bulb holder, a reflector, a lamp bulb projecting through said reflector into said holder, a battery within said casing in electrical contact with one terminal of said lamp, means for moving the battery 110 longitudinally of the casing for shifting the position of said lamp bulb with respect to said reflector, and means for moving said reflector while maintaining operative relation between said battery and said lamp.

12. In a battery hand lamp, the combination of a casing, a battery therein, a lamp in electrical connection with said battery, a socket for said lamp, a yielding disk supporting said socket, a reflector for said lamp 120 having a central opening through which the bulb of the lamp will pass, and means for moving said reflector while maintaining operative relation between said battery and said lamp.

13. In a battery hand lamp, a metal casing, a reflector carried at one end of said casing, a movable bulb holder within said

- casing, a lamp bulb projecting through said reflector into said bulb holder, a battery in electrical contact with said lamp bulb and movable longitudinally of said casing, means 5 for completing the battery circuit through the lamp bulb, means for preventing short circuiting of the battery when the lamp bulb is removed or when its filament is broken, and means for adjusting the position of the 10 battery to focus the lamp.
14. In a battery hand lamp, the combination of a yieldably mounted bulb holder, a battery, and means movable with the bulb holder to insulate said holder from the battery when the bulb is removed from said holder to prevent short circuiting of the battery.
15. In a battery hand lamp, the combination of a longitudinally yieldable bulb 20 holder, a reflector, a battery, means carried by the bulb holder to insulate the same from the battery when the bulb is removed from the holder, and means for moving the battery to adjust the position of the bulb holder 25 with relation to the reflector.
16. In a battery hand lamp, a reflector, a bulb holder, a bulb carried by said holder, means for mounting said bulb holder so as to permit spring resisted movement of the 30 same along the axis of the reflector, a battery, an insulating element movable with said bulb holder and located between the same and said battery for preventing short circuiting of the battery when the bulb is 35 removed from its holder, and means for moving the battery to focus said lamp.
17. In a battery hand lamp, a casing, a battery carried therein, a reflector, a movable bulb holder, a bulb in said holder, a cap threaded to one end of said casing, and means carried by said cap, and forming an 40 abutment for said battery whereby said lamp may be moved with relation to said reflector by movement of said cap.
18. In a battery hand lamp, a casing, a reflector carried at one end of said casing, a bulb holder movable with respect to said reflector, a bulb carried by said holder, a battery movable within said casing, a threaded cap closing the other end of said casing, and means between said battery and said 50 cap forming an abutment for said battery whereby the battery may be moved to adjust the position of said bulb with respect to said reflector.
19. In a flashlight, a reflector, an aperture in the reflector, an incandescent bulb adapted to move along a line passing through said aperture, a spring arranged to 60 urge said bulb in one direction, and a battery adjustable with respect to the reflector and arranged to variably position the bulb therein.
20. A portable focusing electric light com- 65 prising the combination of a reflector member; an incandescent lamp member associated therewith; one of said members being adjustable relatively to the other of said members, a battery for energizing said lamp member; a casing carrying said reflector, 70 lamp, and battery axially in alinement; and means for adjusting the said members relatively to one another comprising means for moving said battery and the adjustable member as a unit axially of said casing. 75
21. A portable focusing electric light as claimed in claim 20, wherein such adjusting means comprises resilient means yieldingly opposing the movement of said unit in one 80 direction.
22. A portable focusing electric light as claimed in claim 20, wherein such moving means comprises a device adjustable rotatably and axially relatively to said casing. 85
23. A portable focusing electric light comprising the combination of a reflector member, an incandescent lamp member associated therewith; one of said members being adjustable relatively to the other of said members, a battery for energizing said lamp 90 member; a casing carrying said reflector, lamp, and battery axially in alinement; and means for adjusting said battery and the adjustable member as a unit axially of said casing and relatively to the other of said 95 members to focus the light from said lamp, such means comprising a cap adjustably coupled to one end of said casing.
24. A portable focusing electric light comprising the combination of an incandescent 100 lamp; a battery for energizing said lamp; a reflector having an opening through which said lamp projects; a casing carrying said battery, lamp, and reflector in axial alinement; and means operative to adjust said 105 lamp and said reflector axially relatively to one another to focus the light from said lamp, such means including spring means disposed between said reflector and said battery. 110
25. In a flashlight, the combination of an incandescent lamp; a battery operatively associated with said lamp; a casing for said battery; a support substantially closing one end of said casing and comprising an insulating member fitting in said casing and a current-conducting member carried by said insulating member; a holder for said lamp carried by said support and in circuit with said current-carrying member; and a reflector associated with said lamp and movable axially of said casing without disturbing the operative relation of said lamp to said battery. 115
26. In a focusing flashlight, the combination of a battery; an incandescent lamp in circuit therewith; a tubular casing for said battery and coaxial therewith; a support 120
- 125

substantially closing one end of said casing and comprising an annular insulating member fitting in said casing and current-conducting member carried by said insulating member; a threaded socket for said lamp carried by said support; a reflector insulated from said socket and having a central open-

ing through which said lamp projects; and means whereby said reflector is adjustable axially of said socket and said lamp to focus the light from said lamp.

In testimony whereof, I have affixed my signature to this specification.

JOSEPH T. ROFFY.
